ABSTRACT OF THE DISCLOSURE

In a magnetic digital ammeter unknown analog currents are compared with known digital inputs in a single core for comparison purposes. The core has a magnetic characteristic of a high permeability at the origin with a very small cross-section whereby small magneto motive forces will saturate the core material. The comparison of the analog signals to the digital signals is accomplished by causing both magneto motive forces produced by the two signals to go toward zero and noting the polarity of the back electro motive force developed. The series of back E.M.F. or "kik" polarities is employed to alter the digital MMF so that it approaches the signal MMF in magnitude. The very small cross-section of the core permits rapid switching since a large net MMF decreases towards a minimal net MMF with little delay owing to the need for a large change of flux.

BACKGROUND OF THE INVENTION

(1) Field of the invention

This invention is directed generally towards improvements in code converters and more particularly is directed towards a new and improved system for converting unknown electrical currents into known digital data. The system may be defined as a magnetic digital ammeter.

(2) Description of the prior art

In my U.S. Pat. No. 3,231,886 dated Jan. 25, 1966, there is disclosed a system for converting an analog current to decimal digits. The system described and illustrated therein includes a magnetic core in which signal magnetizing forces opposed digital magnetizing forces. The polarity of the net magnetizing force in the core is sensed by causing both analog and digital signals to go to zero to produce a back E.M.F. or "kik." The polarity of the backpulse E.M.F. was used to alter the digital MMF so that it approached the signal MMF. Within a short time, the two opposing MMF's were closely equal and the digital MMF's switches could be read out as a number. In this manner the analog signal is converted into a digital display. The present invention concerns itself with improvements on the above converter and specifically relates to a novel core circuit arrangement for improving the speed, stability, economy, precision and resolution of a magnetic digital ammeter. Speed is increased by reducing the time required to arrive at equality between the analog and digital signals, this time being the period required to produce the magnetic flux change. The present system is adapted to detect small net MMF's without causing the signal current in the converter to go to zero. This invention features means for changing the digital MMF by a change of winding turns only, thus giving an increase in stability and an economy in the use of precision resistors employed in the circuit. The invention also features means to minimize the effect of the "kik" polarity of very small mismatch of times on switching the MMF's toward zero.

2

SUMMARY OF THE INVENTION

The invention features a magnetic digital ammeter comprising a core of very small cross-section and having a magnetic characteristic of a high permeability slope at the origin. The core is provided with three sets of windings, one set for applying unknown analog signals to the core, another set for applying known digital signals to the core in a direction opposing the analog signals and a third set for detecting the polarity of the net MMF. The digital windings are connected to a precision resistor and switching means, responsive to the detected polarity in the core, are provided for causing a change in the number of digital turns whereby a single precision current through a single precision resistor may be employed to give a plurality of different MMF's corresponding to a decimal digit, all of these MMF's being stable.

BRIEF DESCRIPTION OF THE DRAWINGS

20 FIG. 1 is a curve showing the magnetic characteristics of a transformer in the form of an annular core employed in the invention,

25 FIG. 2 is a somewhat schematic diagram of the windings on the transformer core and their associated circuitry, and

FIG. 3 is a timing diagram illustrating the sequence of opening and closing of the several switches in the circuit.

DESCRIPTION OF THE PREFERRED EMBODIMENT

30 Referring now to FIG. 1 of the drawings, there is shown the magnetic characteristic curves of two different annular transformer cores for use in comparing known digital MMF's to unknown analog signal MMF's. The broken line curve 4 is for a core of the type employed in my U.S. Pat. 3,231,886 and the solid line curve 5 is for a core used in the present invention. In the curves of FIG. 1 the horizontal axis 2 represents MMF (magnetic force) and the vertical axis 1 represents magnetic flux (field strength). A vector 8 represents a signal MMF which is almost equal to an opposing digital MMF indicated by a vector 7 so that a net MMF appears as a small vector indicated by reference character 9. The polarity of the vector 9 is detected by causing both MMF's, indicated by vector lines 7 and 8 respectively, to go toward zero. This will cause a flux change in the negative or down direction of that small part of the magnetic characteristic curve 3.

50 At the start of the balancing process the digital MMF is reset to zero. It is then evident that the net MMF will be a large vector to the right as viewed in FIG. 1. As this net MMF becomes smaller, the flux will have to change down along the curve 4. A large flux change corresponding to the high slope of the curve 4 means that a large volts-time product is required to force this flux. That is to say it will take a relatively long time to approach a balanced condition within the core.

55 A high initial permeability (slope) can be achieved and yet limit the above flux change if the material be such as sold under the trademark "Supermalloy" but having a cross-section which will be minimal, typically on the order of a few wraps of $1/8$ mil tape for a saturation flux change of about 5.0 maxwells. This characteristic is represented by the curve 5 and 5' in FIG. 1 and yields a higher speed in matching MMF's than the curve 4 to 4' characteristic which represents a core fabricated according to my 3,231,886 patent.

Referring now more particularly to FIG. 2, there is shown schematically three sets of core windings namely, a digital winding 10, an analog winding 22 and a sense winding 28. It will be understood that all windings 12, 22 and 28 are wrapped about a common annular transformer core in the same general manner as shown in my Pat. 3,231,886. In FIG. 2 the reference character 17 indicates a precise current generated in the digital circuit by a precise resistor in series to a precise voltage. An unknown signal current is shown at 26 in the circuit for the analog winding 22. These currents give rise to MMF's in both windings 10 and 22 and these MMF's are caused to go towards zero when switches, indicated at 19 in the digital circuitry and at 25 in the analog circuitry, move at the same time to positions 20 and 24 respectively. While these switches are shown as relay types, this is only for illustrative purposes and in practice, the switches would be a pair of transistors.

In operation the digital MMF is changed by switching the current by means of a switch 16 to a different tap on the winding 10. Thus, for example, a net MMF, such as indicated by vector 9 in FIG. 1, indicating that the analog signals exceed the digital signals, might mean that the digital current transfers from tap 12 to tap 13 as shown in FIG. 2, this being an increasing in MMF. It will be noted that the current remains the same, that is, there is only one precise resistor per decimal digital (10 tap positions).

If the signal current 26 is not rerouted exactly at test time, then the signal MMF, indicated by the vector 8 in FIG. 1 will stay constant as the digital MMF, indicated by vector 7 in FIG. 1, goes toward zero. Then, if the signal exceeds the digits producing a net MMF, such as indicated at vector 9 in FIG. 1, then the resulting change of MMF from vector 9 to vector 8 will not pass through the very narrow region 3 on the curve 5 of high permeability. That is to say, there will be very little flux change and "kik" voltage, thus the two opposing MMF's will be compared on the basis of kik voltage without rerouting the signal current.

In very precise instruments, it is important that both switches 19 and 25 operate within a fraction of a microsecond of one another. This is true when there is an appreciable resistance, indicated at 29 in the sense circuitry, as then the kik can be large. That is, let the switch 25 operate an instant before the switch 19, then in that instant, which is the lag time of the switch 19, there will be a large MMF indicated by the vector 7, which will cause an appreciable flux change due to the false large kik.

In FIG. 2 a switch 30 is shown as a short circuit across the sense winding 28. Let the switches operate in the sequence indicated in FIG. 3 which includes the lag time of the switch 19. In this case, a pull towards a large steady state net MMF during this lag cannot appreciably alter the condition of the true net MMF, since the short circuit does not allow voltage and therefore flux change. That is to say that the L/R time constant for a change of MMF is very much longer than the lag time. Then, subsequently, the opening of the switch 30, as shown in FIG. 3, permits the true "kik" which is then detected and used to alter the digital MMF appropriately.

Having thus described the invention, what I claim and desire to obtain by Letters Patent of the United States is:

1. A magnetic digital ammeter, comprising:

- (a) a core,
- (b) said core being formed of magnetic material of small cross-section and characterized by initially high permeability,
- (c) analog, digital and sense windings wound about said core,
- (d) first means for applying unknown signals to said analog windings to produce a magnetic force in said core in one direction,

- (e) second means for applying known digital signals to said digital winding to produce a magnetic force in said core in a direction opposite to the unknown force,
- (f) switching means connected to said analog and digital windings for causing both of said forces to go to zero force and thus produce a back electro-motive force having a net force in either of said directions,
- (g) third means connected to said sense winding to detect the polarity of said net force,
- (h) a series of taps connected to said digital windings,
- (i) a switch connected to said second means and adapted to connect to a selected tap,
- (j) said switch being responsive to said third means to position said switch with respect to said taps and thereby increase said digital signals until the known digital force balances the unknown analog force,
- (k) switching means connected to said sense winding, and
- (l) timing means connected to said switching means for first actuating the switching means for said sense winding to short circuit said sense winding then actuating the switching means for said analog and digital windings to cause said forces to go to zero force in close timed relation to produce a back electro-motive force of a certain polarity whereby the lag time between the analog and digital switching means will not appreciably alter the operating point of said core, said sense switching means then opening to sense a pulse of a polarity of the original net force.

2. A magnetic digital ammeter, comprising:

- (a) a core of magnetic material having a hysteresis curve characterized by a narrow region of high permeability in the center of said curve and low permeability elsewhere on said curve,
- (b) analog, digital and sense windings disposed about said core,
- (c) means for applying through said analog and digital windings opposing magnetizing forces to said core,
- (d) said sense winding adapted to detect the polarity of the net force in said core,
- (e) a series of taps connected to said digital winding,
- (f) a precise current source,
- (g) a switch connected to said source and adapted to connect to a selected tap,
- (h) said switch being responsive to the output of said sense winding to position said precise current with respect to said taps,
- (i) switching means connected to each of said analog, digital and sense windings, and,
- (j) timing means connected to said switching means for first actuating the switching means for said sense winding to short circuit said sense winding then actuating the switching means for said analog and digital windings to cause said forces to go to zero force in close timed relation to produce a back electro-motive force of a certain polarity whereby the lag time between the analog and digital switching means will not appreciably alter the operating point of said core, said sense switching means then opening to sense a pulse of a polarity of the original net force.

3. A magnetic digital ammeter comprising:

- (a) a core of magnetic material having a high initial permeability,
- (b) analog, digital and sense windings disposed about said core,
- (c) means connected to said analog and digital windings for applying opposing magnetic forces to said core,
- (d) a switch provided for each of said windings and operatively connected to one another for operation in timed sequence,

(e) timing means connected to said switches for first actuating the switch for said sense winding to short circuit said sense winding then actuating said analog and digital switches to cause said opposing forces to go to zero force in close timed relation to produce a back electro-motive force of a certain polarity whereby the lag time between said analog and digital switches will not appreciably alter the operating point of said core, said sense switch then opening to sense a pulse of a polarity of the original net MMF.
